UNITED STATES PATENT OFFICE.

WILLIE E. HOUGAS AND FERDINAND W. RAUCH, OF LAMONI, IOWA.

WIRE-SPlicer.

1,072,332.

Specification of Letters Patent.

Patented Sept. 2, 1913.

Application filed May 9, 1912, Serial No. 696,111. Renewed February 7, 1913. Serial No. 746,928.

To all whom it may concern:

Be it known that we, WILLIE E. HOUGAS and FERDINAND W. RAUCH, citizens of the United States, residing at Lamoni, in the county of Decatur and State of Iowa, have invented certain new and useful Improvements in Wire-Splacers, of which the following is a specification.

Our invention relates to devices for splicing wires and consists in the provision of a splicer of the plier type having the sides of the jaws provided with grooves to receive the wire to be spliced and a transverse opening in the jaws to receive the wire on which the splice is to be made.

Our invention has for its object the provision of means by which a splice can be effected by means of plier type tools by giving them a motion through an arc of 90° instead of as is generally necessary through an arc of 180° or a complete circle rotation.

Our invention also has for its object the provision of a tool of the type described having a provision for splicing wires of different thicknesses.

Our invention will be described in detail hereinafter and illustrated in the accompanying drawings, in which,

Figure 1 is a side view in elevation of our improved tool showing it applied to a splice; Fig. 2, an edge view of the tool; and Fig. 3, a side view of the opposite side to that shown in Fig. 1.

In the drawings, similar reference characters will be used to designate corresponding parts throughout the several views.

Our improved wire splicing tool consists of the plier type tool indicated at 1 having its two jaws pivotally secured together at 2, the two jaws being formed as shown with substantially semicircular formations 3 and 4 on one side and 5 and 6 on the other side. Each of said semicircular formations has a groove running parallel with the engaging edges of the jaws designated 7, the groove in the formation 3 being indicated 3^a that in 4, 4^a, in 5, 5^a, and in 6, 6^a. Each of said jaw members is also provided with a groove perpendicular to the grooves just described and indicated at 3^b in jaw 3, 4^b in jaw 4, 5^b in jaw 5, and 6^b in jaw 6. The jaws are also

provided with a central opening indicated at 8, to receive the line wire 9 on which the splice is to be made.

In use, it will be apparent that the improved tool as shown in Fig. 1 may be used in making splices in wire structures, the opening 8 being formed to receive the wire on which the splice is to be made and indicated at 9 in Fig. 1. The wire that is spliced on the wire 9 indicated at 10 is wrapped around the wire 9 by means of our tool, the free end of the wire being engaged by one of the grooves on one of the faces of the jaws and by giving the tool a quarter turn, it will be apparent that an effective splice may be made. By providing the jaws with grooves of different widths as shown in the drawings, it will be apparent that our tool is adapted to use with wires of different thicknesses as the smaller grade wires are adapted to be operated upon by the jaw faces 3 and 4, while the heavier wires are operated upon by the jaws 5 and 6.

Having thus described our invention what we claim is:—

1. A wire splicer of the plier type having its jaws provided with grooves on its two sides arranged crosswise of one another and of different widths.

2. A wire splicer of the plier type having its jaws provided with two faces having grooves on each face arranged crosswise of one another and at right angles to each other, and the grooves on the two faces of the jaws of different widths.

3. A wire splicer of the plier type having the meeting edges of its jaws formed with openings to receive a line wire, the two faces of the jaws formed with grooves arranged at right angles to one another and radially of said openings, the grooves on the two sides of the jaws being of different widths and adapted to receive the end of the splicing wire.

In testimony whereof we affix our signatures in presence of two witnesses.

WILLIE E. HOUGAS.
FERD. W. RAUCH.

Witnesses:

OSSA TEALE,
W. B. NICHOLSON.
